UNITED STATES PATENT OFFICE.

HELEN BOOGIE LEMMON, OF CORNELIUS, OREGON.

SECURITY-ENVELOP.

1,122,234.

Specification of Letters Patent. Patented Dec. 22, 1914.

Application filed January 16, 1913. Serial No. 741,234.

To all whom it may concern:

Be it known that I, HELEN BOOGIE LEMMON, citizen of the United States, residing at Cornelius, in the county of Washington and State of Oregon, have invented certain new and useful Improvements in Security-Envelops; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in tab lock envelopes, made preferably from a single piece of paper or other material and so constructed that the blank, when folded upon the envelop, may be securely sealed and affording a closure whereby the flaps may not be opened without detection.

The invention consists of a device of this nature having various details of construction and combinations and arrangements of parts which will be hereinafter fully described, shown in the accompanying drawings and then specifically defined in the appended claim.

I illustrate my invention in the accompanying drawings, in which—

Figure 1 is a plan view of the blank of paper out of which the envelop is formed, showing in dotted lines two of the flaps folded. Fig. 2 is a view of the face of the envelop with the end flaps in readiness to be turned down and sealed, and Fig. 3 is a similar view showing the flaps folded and sealed.

Reference now being had to the details of the drawings by letter, A designates the blank of paper out of which the envelop is formed and which is provided with laterally formed wings B and C, adapted to fold upon the lines D and E respectively to assume the positions shown in dotted lines in Fig. 1, in which one flap or wing overlaps the other. Said flaps are adapted, when folded as shown in dotted lines, to be again folded along the dotted line F, as shown in Fig. 1 of the drawings, thus forming the wall of the closure of the envelop when the

envelop is formed. At one end of the blank is a flap H which is adapted to be folded along the line H' and formed centrally in the flap H is a slot K adapted for the reception of the integral tongue N which is formed at the opposite edge of the blank of paper. Along the marginal edge from which the tongue N projects is a flap O which is adapted to fold upon the line O' after the parts have been folded to assume the position shown in Fig. 2 of the drawings.

The under surface of the flap H is coated with a gummed or adhesive material and is wider than the flap O over which it is adapted to fold, as shown in Fig. 3 of the drawings, when the envelop is sealed and after the tongue has been inserted through the slot K formed in the flap H. It will be noted that the marginal edge of the flap O adjacent to the tab is contracted somewhat for the purpose of allowing a greater width of the adhesive surface of the flap H to be securely sealed to the blank about said tongue and the face of the tongue is also provided with an adhesive coating and is adapted to be fastened to the outer face of the flap O and to the outer face of the front or address receiving surface of the envelop, thus affording a means for securely holding the flaps of the envelop sealed. In order to insure further sealing of the envelop, a postage stamp, designated by dotted lines in Fig. 4 of the drawings, may be placed over the tongue and the flap.

By the provision of an envelop made in accordance with my invention, a simple and efficient means is afforded whereby an envelop may be securely sealed and one which may not be opened without detection.

What I claim to be new is—

An envelop comprising a sheet of material with two oppositely disposed wings and a laterally extending wing intermediate the latter, said oppositely disposed wings being adapted to be folded along lines in alignment with the opposite ends of the laterally extending flap, the two oppositely disposed flaps, when folded one over the other, being adapted to be folded upon themselves together with a portion of the blank and the end of the laterally extending flap projecting beyond the parts thus folded and having

a slit formed therein, an integral tab projecting from one edge of the blank opposite the laterally extending flap and provided with a wing upon either side of the tab designed to be folded back upon the face of the blank, said tongue adapted to be passed through said slit and the projecting portion having the slit designed to fold over said

wing and be secured to the face of the envelope.

10

In testimony whereof I hereunto affix my signature in the presence of two witnesses.

HELEN BOGIE LEMMON.
